His Attorney.

UNITED STATES PATENT OFFICE

REGINALD G. STANDERWICK, OF MARBLEHEAD, MASSACHUSETTS, ASSIGNOR TO
GENERAL ELECTRIC COMPANY, A CORPORATION OF NEW YORK

GOVERNING MECHANISM FOR TURBINE-DRIVEN SETS

Application filed December 24, 1927. Serial No. 242,351.

The present invention relates to turbine-driven sets and especially to governing means for such sets.

The object of my invention is to provide an improved governing mechanism for such sets, and for a consideration of what I believe to be novel and my invention, attention is directed to the accompanying description and the claims appended thereto.

One application of my invention is in connection with turbine-driven centrifugal compressors wherein the speed is governed by an operating condition other than the speed of the set, for example, the volume of fluid supplied to the compressor, and also by the speed of the set, and in the present application, I have elected to illustrate specifically this application of my invention. It is to be understood, however, that this is only by way of example and that my invention is not limited thereto except where specifically so stated in the claims.

In the drawing, the figure is a diagrammatic view of a turbine-driven centrifugal compressor provided with a governing mechanism embodying my invention.

Referring to the drawing, 1 indicates an elastic fluid turbine having an inlet conduit 2 and an exhaust conduit 3, and 4 indicates a centrifugal compressor having an inlet conduit 5 and a discharge conduit 6. This turbo-compressor set is shown only diagrammatically and is to be taken as indicating any suitable type of turbine and of centrifugal compressor.

In conduit 2 is provided a valve means 7 for controlling the admission of elastic fluid to the turbine. Valve means 7 is connected by a stem 8 to a lever 9 pivoted at one end on a fixed support 10. The other end of lever 9 is provided with a roller 11 which rests on a cam 12 carried by a cam shaft 13. When cam 12 turns in a clockwise direction as indicated in the drawing, it operates on roller 11 to lift the right hand end of lever 9, thereby opening valve means 7, while when it turns in the opposite direction, the valve means 7 is permitted to close. Cam 12 is turned to effect movement of valve means 7 by a fluid actuated motor comprising a cylinder 14 in

which is a piston 15. Connected to piston 15 is a piston rod 16 having a rack 17 on its upper end which engages a gear wheel 18 fixed on cam shaft 13. Piston 15 is normally forced downward in the cylinder by means of a spring 19. The pilot valve structure of the fluid actuated motor which controls the admission of actuating fluid to cylinder 14 comprises a pilot valve casing 20 in which are located pilot valves 21 and 22 carried by a stem 23. Pilot valve 21 controls the flow of actuating fluid from a pipe 24 to the underside of piston 15 and pilot valve 22 controls the discharge of actuating fluid from the underside of piston 15 out through a discharge passage 25.

When pilot valves 21 and 22 are in the positions shown in the drawing, pilot valve 21 shuts off the end of pipe 24 to prevent the flow of fluid under pressure to cylinder 14 while pilot valve 22 shuts off passage 25 to prevent the flow of fluid from cylinder 14. Piston 15 is therefore held in the position shown against the action of spring 19 by the fluid pressure trapped beneath it. If pilot valves 21 and 22 are raised, fluid is admitted from pipe 24 to the underside of piston 15 to force it upward, thereby opening valve means 7 further while if pilot valves 21 and 22 are lowered fluid is permitted to escape from the underside of piston 15 out past pilot valve 22 thereby permitting piston 15 to move downward effecting a closing of valve means 7. Pilot valve stem 23 is connected to one end of a lever 26 pivoted on a fulcrum 27. The other end of lever 26 is connected by a link 28 to a floating lever 29. The left hand end of floating lever 29 is connected to piston rod 16, forming thereby a usual type of follow up connection. The right hand end of floating lever 29 is connected by a link 30 to one end of a lever 31 pivoted on a fixed fulcrum 32.

The right hand end of lever 31 is connected to the piston rod 33 of a fluid-actuated motor comprising a cylinder 34 in which is located a piston 35. 36 is a spring normally forcing piston 35 downward. Cylinder 34 beneath piston 35 is connected by a passage 37 to a pilot valve casing 38. In pilot valve casing 100

38 is a pilot valve sleeve or liner 39 provided with a passage 40 which forms a continuation of passage 37 and also with passages 41 which communicate with an annular chamber 42 in 5 pilot valve casing 38. Pilot valve sleeve 39 is connected by a link 43 to lever 31. Inside pilot valve sleeve 39 is a pilot valve 44 which controls passages 41 and a pilot valve 45 which controls discharge passages 46 in 10 sleeve 39 which passages communicate with an oil tank 47. Pilot valves 44 and 45 are connected together and to a speed governor 48 of suitable construction, the same being carried by a vertical shaft 49 driven from the 15 turbine shaft by a worm drive 50. Vertical shaft 49 extends down into oil tank 47 and its lower end is connected to drive an oil pump 51 which provides fluid pressure for actuating the governing mechanism and also, 20 if desired, for the lubricating system of the set. 52 indicates the suction inlet of oil pump 51 and 53 indicates the discharge pipe. Oil pump 51 may be, with advantage, of the gear type. In pipe 53 is a suitable pressure relief 25 valve 54. Pipe 24 is connected to pipe 53 as is indicated at 55. At 56 is indicated a branch pipe which may lead to the lubricating system of the turbine-driven set. Pipe 53 extends up to and is connected to a pilot valve 30 casing 57 in which is a pilot valve 58, it being connected to pilot valve casing 57 above the pilot valve. Pilot valve 58 controls a passage 60 which is connected by a pipe 61 to annular chamber 42 in pilot valve casing 38. When 35 pilot valve 58 is lowered it permits fluid pressure to flow from pipe 53 through the pilot valve casing into pipe 61 while when pilot valve 58 is raised it permits fluid from pipe 61 to flow downward through discharge passage 59. The stem 62 of pilot valve 58 is connected to a floating lever 63. One end of floating lever 63 is connected by a link 64 to one end of a lever 65 pivoted on a fulcrum 66. The other end of lever 65 is connected by a 45 link 67 to lever 31. The left hand end of floating lever 63 is pivotally connected to one end of a lever 68 mounted on a fulcrum 69. Connected to lever 68 by a stem 70 is the movable element of a device responsive to the rate 50 of flow of fluid to compressor 4. In the present instance this flow-responsive device is shown as comprising a casing 71 in which is an annular chamber 72 containing a sealing liquid 73. In casing 71 is an inverted bell 74 the edges of which are sealed in sealing liquid 73, the bell being connected to stem 70. In conduit 5 is a pressure difference-creating device 75 which creates a pressure difference which bears a definite relation to 55 the rate of flow of fluid in conduct 5. In the present instance a known form of flow nozzle is indicated. The high pressure or leading pressure side of flow nozzle 75 is connected by a pipe 76 to the underside of inverted bell 65 74 and the low pressure or trailing pressure

side of flow nozzle 75 is connected by a pipe 77 to the other side of inverted bell 74. Bell 74 is thus subjected to a differential pressure which tends to move it in accordance with the rate of flow of fluid through conduit 5, 70 the bell being forced upward as the flow increases and moving downward as the flow decreases. This is a known type of apparatus and is to be taken as typical of any suitable arrangement responsive to rate of flow through conduit 5. 78 is a dash pot for 75 stabilizing the movements of lever 68, and 79 is a weight adjustable along lever 68 to set the mechanism for the desired volume of flow.

The mechanism comprising flow nozzle 75, 80 inverted bell 74 and the lever 68 to which inverted bell 74 is connected forms what is termed usually a constant volume governor, it being understood that a constant volume governor is a governor which responds to rate 85 of flow of fluid to the compressor and serves to adjust the speed of the turbine to maintain the volume at a desired amount. If the volume increases above normal, the constant volume governor operates to decrease the 90 speed of the turbine to bring the volume back to normal and if the volume decreases below normal the constant volume governor operates to increase the speed of the turbine to bring the volume back to normal. By adjusting weight 79 along lever 68, the constant 95 volume governor may be set for the desired volume.

The operation is as follows:

Assume that the turbine is running at a 100 predetermined speed, valve means 7 being partially open, and that at such speed the compressor 4 is handling the volume of fluid for which the constant volume governing mechanism is set. Speed governor 48 forms what 105 is termed usually a pre-emergency governor. It is set for a speed higher than that at which the turbine is expected to run under the control of the constant volume governing mechanism but at a speed lower than that for 110 which the usual emergency governor would be set. It comes into action to take control of the turbine in case the speed exceeds a predetermined high value. Under the assumed conditions, the weights of the speed governor 115 are in their innermost positions, pilot valves 44 and 45 being moved upward to the top of their movement and uncovering the passages 41. Pilot valve 58 covers the end of pipe 61 so that no fluid pressure is being fed past it 120 through the pipe 61 to cylinder 34. Also, pilot valve 21 covers the end of pipe 24 so that no fluid pressure is being supplied from pipe 24 to the underside of piston 15, and pilot valve 22 is positioned to prevent flow of 125 fluid from beneath piston 15. Assume now that the volume of fluid flowing through conduit 5 to the centrifugal compressor 4 increases, which means that valve means 7 130 should be closed somewhat so as to reduce the

speed of the turbine and bring the volume back to normal. When the rate of flow through conduit 5 increases, the pressure difference applied to inverted bell 74 increases thereby lifting the bell somewhat and raising the right hand end of lever 68. This in turn raises the left hand end of lever 63, the same pivoting on the lower end of link 64. Raising the left hand end of lever 63 lifts pilot valve 58 thereby connecting the pipe 61 to discharge passage 59. As a result of this, fluid pressure flows from beneath piston 35 in cylinder 34 through passages 37, 40 and 41 to annular chamber 42 and thence through pipe 61 to discharge passage 59. As a result, spring 36 moves piston 35 downward. Downward movement of piston 35 lowers the right hand end of lever 31 and raises its left hand end thereby through link 30 lifting the right hand end of lever 29. Lifting the right hand end of lever 29 turns lever 26 on its pivot 27 in a direction to lower pilot valves 21 and 22. The lowering of pilot valve 22 permits actuating fluid to escape from beneath piston 15 whereupon spring 19 forces piston 15 downward, moving valve means 7 toward closed position and hence decreasing the amount of elastic fluid admitted to turbine 1 and hence the speed of the turbine. When piston 15 moves downward it carries with it the left hand end of floating lever 29. This serves to lower the right hand end of lever 26 through link 28 thereby lifting the left hand end of lever 26 and restoring pilot valves 21 and 22 to their former normal positions. When piston 35 moves downward in cylinder 34 it pulls down on right hand end of lever 31 thereby turning lever 31 on its pivot 32 and through link 67 raising the right hand end of lever 65. Lever 65 is thus turned on its pivot 66, the left hand end of lever 65 being lowered and through link 64 lowering the right hand end of lever 63, lever 63 pivoting on the end of lever 68. The lowering of the right hand end of lever 63 serves to lower pilot valve 58 restoring it to its former normal position where it covers the end of pipe 61. In case of a decrease in the rate of flow of fluid through conduit 5, an operation similar to that just described, except in the opposite direction would take place, piston 35 being lifted and effecting an upward movement of piston 15 whereby valve means 7 may be opened further.

When the pressure difference set up by pressure difference-creating device 75 decreases, it serves to effect an opening movement of valve means 7, thereby tending to increase the speed of turbine 1. If the constant volume governing mechanism continued to operate to effect opening movements of valve means 7, increasing the speed of the turbine beyond a predetermined amount, then speed governor 48 comes into action lowering pilot valves 44 and 45, the pilot valve 44 covering openings 41. When this happens, pilot valve 58 cannot effect further movement of piston 35 even though it is lowered to uncover the end of pipe 61. Under these circumstances, therefore, the speed governor takes control of the turbine to the exclusion of pilot valve 58 and the constant volume governing mechanism which operates it. In this connection, it will be noted that the pilot valve structure comprising pilot valve casing 57 and the pilot valve 58, which is controlled by the constant volume governing mechanism is in series with the pilot valve structure comprising casing 38, sleeve 29, and pilot valves 44 and 45 and is in advance of it as regards the direction of flow of actuating fluid to cylinder 34. This arrangement serves, so to speak, to place the speed governor 48 in a predominating position over the constant volume governing mechanism.

It will be noted in connection with valve means 7 that the pilot valve comprising casing 20 and pilot valves 21 and 22 for the fluid-actuated motor is moved by the piston 35 of a second fluid-actuated motor, the pilot valves for the second fluid-actuated motor being controlled respectively by the speed governor and by the constant volume governing mechanism.

With this arrangement the pilot valve structure for the fluid-actuated motor comprising piston 15 may be made relatively large in size and arranged directly adjacent to cylinder 14 whereby the flow of fluid to and from cylinder 14 can be effected through large passages so as to reduce to a minimum the time lag in the operation of piston 15. Since pilot valves 21 and 22 are operated by a piston 35 ample power for moving them may be provided. On the other hand, since fluid-actuated piston 35 is required only to move the pilot valves 21 and 22, it may be made relatively small and the pilot valves for it may be made relatively small and light in weight. As a result the speed governor and the constant volume governor are required to move only small pilot valves whereby the work which they are required to do is little. As a result the speed governor and the constant volume governor may be made as sensitive as desired.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

1. In combination, a turbine-driven set having valve means for controlling the admission of actuating fluid to the turbine, a fluid-actuated motor for positioning said

valve means, a plurality of pilot valves controlling the flow of fluid pressure to said motor, said pilot valves being arranged in series as regards the flow of fluid through them, governing means responsive to one operating condition of the set for positioning one of said pilot valves, and governing means responsive to another operating condition of the set for positioning another of said pilot valves.

2. In combination, a turbine-driven set having valve means for controlling the admission of actuating fluid to the turbine, a fluid-actuated motor for positioning said valve means, a plurality of pilot valves controlling the flow of fluid pressure to said motor, said pilot valves being arranged in series as regards the flow of fluid through them, governing means responsive to the speed of the set for positioning one of said pilot valves, and governing means responsive to an operating condition of the set other than its speed for positioning another of said pilot valves, said speed-responsive pilot valve being located between the one pilot valve and the fluid-actuated motor.

3. In combination, a turbine-driven set having valve means for controlling the admission of actuating fluid to the turbine, a fluid-actuated motor for positioning said valve means, a pilot valve controlling the admission of actuating fluid to said motor, a second fluid-actuated motor for moving said pilot valve, a plurality of pilot valves for controlling the flow of actuating fluid to said second fluid-actuated motor, said valves being arranged in series as regards the flow of fluid through them, governing means responsive to one operating condition of the set for positioning one of said plurality of pilot valves, and governing means responsive to another operating condition of the set for positioning another of said plurality of pilot valves.

4. In combination, a turbine-driven set having valve means for controlling the admission of actuating fluid to the turbine, a fluid-actuated motor for positioning said valve means, a plurality of pilot valves controlling the flow of fluid pressure to said motor, said pilot valves being arranged in series as regards the flow of fluid through them, governing means responsive to an operating condition of the set for positioning one of said pilot valves, and means for positioning another of said pilot valves.

5. In combination, a turbine-driven set having valve means for controlling the admission of actuating fluid to the turbine, a fluid-actuated motor for positioning said valve means, a plurality of pilot valves controlling the flow of fluid pressure to said motor, said pilot valves being arranged in series as regards the flow of fluid through them, a speed governor for positioning one

of said pilot valves, said speed governor being set for a speed higher than normal operating speed, and means for positioning another of said pilot valves.

In witness whereof, I have hereunto set my hand this 21st day of December, 1927.

REGINALD G. STANDERWICK.
